DESIGN FOR A DRESS

David E. Gottlieb, New York, N. Y.

Application August 12, 1942, Serial No. 107,892

Term of patent 3½ years

To all whom it may concern:

Be it known that I, David E. Gottlieb, a citizen of the United States of America, residing in New York city, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

Fig. 3 is an enlarged fragmentary view of the

dress shown in Fig. 1 in a flat position showing one of the embroidered pocket members in detail.

The characteristic feature of my design resides in the combination on the dress disclosed of the specific pocket members which are embroidered and trimmed as shown.

I claim:

The ornamental design for a dress, substantially as shown and described.

DAVID E. GOTTLIEB.
